UNITED STATES PATENT OFFICE.

JOHN Y. KING, OF LANSDOWNE, PENNSYLVANIA.

AIR-FEEDING DEVICE.

1,405,520.

Specification of Letters Patent. Patented Feb. 7, 1922.

Application filed December 23, 1920. Serial No. 432,710.

To all whom it may concern:

Be it known that I, JOHN Y. KING, a citizen of the United States, residing at Lansdowne, in the county of Delaware and 5 State of Pennsylvania, have invented new and useful Improvements in Air-Feeding Devices, of which the following is a specification.

My invention relates to a new and useful 10 improvement in air feeding devices for coal burning furnaces, and has for its object to provide an exceedingly simple and effective device of this description which may be readily applied to the door of a coal burning 15 furnace and which when so applied will project streams of highly heated air over the fire bed in such manner as to intermingle and combine such air with the gases of combustion causing the latter to burn with intense 20 heat and thus prevent the escape of unburned carbon in the form of smoke or soot.

A further object of my invention is to provide simple and effective means for regulating the flow of air to the device.

25 A still further object of my invention is to provide simple and effective means for attaching the device to the furnace door.

With these and other objects in view, this 30 invention consists in the details of construction and combination of elements herein-after set forth and then specifically designated by the claims.

In order that those skilled in the art to which this invention appertains, may understand 35 how to make and use the same, I will describe its construction in detail, referring by numerals to the accompanying drawing forming a part of this application, in which:—

40 Fig. 1, is a perspective of an air feeding device made in accordance with my improvement.

Fig. 2, is a central longitudinal section of the device, a portion of a furnace door being 45 shown to which the device is attached.

Fig. 3, is a face view of the air regulating disc.

In carrying out my invention as here embodied, 1 represents the body or reservoir of 50 the device which is in the general shape of an elongated casing having a hollow interior 2 into which the air is fed.

3 represents a shank in the form of a tube or pipe having its inner end threaded as indicated at 4 for screwing into the internally 55 threaded boss 5 formed with the cas-

ing, while the outer end of the pipe is threaded as indicated at 6.

7 represents a flared intake member having an internally threaded hub 8 adapted to 60 screw upon the outer end of the pipe 3 and to this intake member is pivoted the regulating disc 9 so as to enclose the interior of the intake member, thereby providing a relatively large space 10 into which the air 65 first passes and from which it flows through the pipe 3 to the interior of the casing 1. This regulating disc has a slot 11 formed therein through which the rivet 12 passes, said rivet being secured in the flange 13 of 70 the intake member; this slot being of such shape as to permit the regulating disc to entirely close the front of the intake member when the rivet is in the upper portion of said slot, while said regulating disc will 75 leave uncovered a certain portion of the intake member when the rivet is in the lower portion of said slot.

A small hole 14 is formed through the regulating disc, said hole having the capacity 80 for normally feeding air to the device.

15 represents a nut run upon the threads 6 for coacting with the intake member to secure the device to the furnace door 16. 85 This securement being effected by removing the intake member from the thread 6, passing the outer end of the pipe through a suitable hole formed in the door and then replacing the intake member and screwing it up so as 90 to draw the nut 15 firmly against the inner face of the door. In order that the device may not be accidentally displaced by jar or vibration, I prefer to interpose a split spring washer 17 between the inner face of the hub 95 8 and the outer face of the door so that when the intake member has been screwed home this washer will act as a friction lock.

In practice when the device is applied to a furnace door and the door is closed the 100 casing 1 projects into the furnace above the coal bed and air flowing into the space 10 in the intake is gradually expanded by the heat transmitted to this intake member and from thence this air passes through the interior 105 of the pipe 3 constantly absorbing a greater amount of heat thereby being expanded until it flows into the reservoir of the casing where it will be superheated and thereby further expanded and finally issuing 110 through the holes 18 in fine jets of streams which commingling with the gases arising

from the fire bed will produce perfect combustion of said gases resulting in intense heat.

The effectiveness of this device depends 5 upon the principle of providing an unobstructed and unbaffled direct passage for the inflowing air which passage permits the air to reach the expansion chamber without being retarded and permits the air to expand 10 suddenly, thereby creating sufficient pressure to deliver jets of highly heated air of such light density over the fire bed as to intensify the combustion after the manner of a blow pipe. Long experience and ex- 15 haustive experiment has shown that this result cannot be obtained when the incoming air is baffled or caused to follow a circuitous route and that it is essential to supply the gases during combustion with a very 20 small amount of air by weight in a highly heated state and at high speed and this can only be accomplished by feeding the inflowing air directly and unobstructedly to the expansion chamber, for if the air is 25 baffled or caused to flow through a circuitous passage its temperature will be gradually raised so that when it reaches the point of delivery it will not be suddenly expanded to a large degree and the delivery will not 30 be at a high speed which is essential to obtaining the desired results.

Of course I do not wish to be limited to the exact details of construction as herein shown as these may be varied within the 35 limits of the appended claims without departing from the spirit of my invention.

Having thus fully described my invention, what I claim as new and useful is:—

1. An air feeding device comprising an 40 elongated rectangular body having holes through one of its longer sides and provided with an internally threaded boss on the other longer side, the interior of said body being unobstructed, a pipe, the inner 45 end thereof having threaded connection with said boss to provide an unobstructed air conduit to the interior of the body, a sepa-

rate flared intake member having threaded connection with the outer end of said pipe, and means also having threaded connection 50 with the outer end of said pipe and coacting with said intake member and an applicance to which the device is secured.

2. A device of the character stated consisting of an elongated rectangular body adapt- 55 ed to be located above a fire bed in a horizontal plane, said body having an unobstructed hollow interior with outlet holes leading therefrom through one of its longer sides in a horizontal line, an unobstructed 60 straight conduit leading directly into the interior of said body at a point opposite the aforementioned line of holes, an air intake member at the end of the conduit opposite the body, and means for regulating the 65 amount of air passing into said air intake member.

3. An air feeding device comprising an elongated rectangular hollow body having holes through one of its longer sides and 70 provided with an internally threaded boss on the opposite longer side, the interior of said body being unobstructed, a pipe, the inner end thereof having threaded connection with said boss to provide an unob- 75 structed air conduit to the interior of said hollow body, a separate intake member connected to the outer end of said pipe and means coacting with said intake member also connected with said pipe. 80

4. An air feeding device comprising a hollow rectangular body forming an air reservoir, holes through one of the longer sides of said hollow body, a pipe connected to the other longer side of said hollow body for 85 feeding air to said reservoir and forming an unobstructed passage for the air through said pipe to the reservoir to permit a sudden expansion of the air at its point of delivery, and regulating means on the other 90 end of said pipe.

In testimony whereof, I have hereunto affixed my signature.

JOHN Y. KING.
